UNITED STATES PATENT OFFICE.

JAMES W. BUTLER, FRED R. BRIGGS, AND EDWIN H. CLARK, OF CLEVELAND, OHIO, ASSIGNORS
TO THE AUTO FUNERAL CAR COMPANY, OF CLEVELAND, OHIO.

BODY FOR AUTO FUNERAL-CARS.

No. 928,179.

Specification of Letters Patent.

Patented July 13, 1902.

Application filed September 10, 1908. Serial No. 452,495.

To all whom it may concern:

Be it known that we, JAMES W. BUTLER, FRED R. BRIGGS, and EDWIN H. CLARK, citizens of the United States, and residents of Cleveland, in the county of Cuyahoga, and State of Ohio, have invented certain new and useful Improvements in Bodies for Auto Funeral-Cars, of which we hereby declare the following to be a full, clear, and exact description, such as will enable others skilled in the art to which it appertains to make and use the same.

The invention applies to the employment of an elegant and attractive funeral conveyance in which no suggestion is found of its serious uses, and the objects of the invention are to provide means for adapting the body of a motor car to undertakers' use as a funeral car, wherein the casket can be conveyed to the tomb, and can be accompanied by the family and the pallbearers and other immediate attendants upon the funeral, and the impression made upon outside observers will not be different from that made by the body of an ordinary Limousine car, thus protecting the mourners from the curious gaze of the community besides adding efficiency and practicability and convenience to the now dreaded ordeal of passing through the streets with a hearse and a long line of carriages.

The invention comprises an inclosed car body arranged to protect the casket and accompanying cortège from the weather and provided with compartments adapted to the several uses of the car.

The invention further comprises instrumentalities adapted to increase the convenience in handling the casket and for seating the pallbearers, and has further reference to the arrangement of fixed and removable or folding seats to accommodate all persons accompanying the body to the tomb.

The invention further comprises the combination and arrangement of the various parts and construction of details as herein-after described, shown in the accompanying drawings, and specifically pointed out in the claims.

In the accompanying drawings, Figure 1 is a side elevation of the completed car; Fig. 2 is a transverse section thereof through the casket chamber looking toward the rear; Fig. 3 is a horizontal section, and Fig. 4 is a detail perspective view of a hinge joint be-

tween the fixed and movable portions of a track hereinafter described.

In these views 1 is the car body containing front and rear compartments and a chauffeur's division D. The front compartment 2 is designed for the conveyance of the casket 3, and about the casket are grouped the seats 4 for the pallbearers.

5 is the rear or passenger compartment and in this are provided stationary and removable or folding seats 6, 6 and 7, 7 respectively, upon which are seated members of the family and their friends.

The entrances to the passenger portion of the car are preferably at the side as at 11, 11 and side aisles 12, 12 can be formed to the rear seats by making the seats 7, 7 hinged and foldable upon the sides of the compartment. The seats 8, 8 are also foldable to provide a transverse aisle 13, in front of the rows of seats.

75 Important features are shown in the manner of constructing the compartment adapted to contain the casket, and of arranging for the introduction and removal thereof and for the seating of the immediate attendants such as the pallbearers.

To permit of the ready introduction of the casket to lie longitudinally of the compartment in which it must be carried, and to permit of quickly and easily removing the same, both sides 14, 14 preferably, of the casket compartment are preferably hinged at 15, 15 so as to be let down into a substantially horizontal position. Upon the inner surfaces of these hinged sides or doors, as they may be called, are shown tracks 16, 16 which are preferably hinged at 15, 15 to the transversely laid tracks 16', 16' upon the floor of the compartment and form continuations of the same when the doors are laid flat. 90 The track hinges 15 preferably form the hinges upon which the doors swing. Shoulders 18, 18 in the hinges serve to prevent the doors from falling too low and they remain when lowered in preferably the horizontal 95 position. These tracks may themselves form the hinge straps if desired.

The casket is placed upon a small wheeled platform 19 which is adapted to run upon the tracks, and can readily be moved in or out 100 of the car. The casket is secured by any suitable adjustable means, such as the pins 20, 20 shown, which are inserted in holes in

the platform, so that a casket of any size can be secured upon the platform. The seats 4 for the attendants in this compartment are arranged about the casket and may be removably secured to the floor, so that they can be temporarily taken away to permit the casket to move over them, or they may be hinged to the doors 14 on their inner sides at 22 as shown in Fig. 2 so that they may be folded flat between the tracks when the doors are lowered, to permit the casket to move over them, and can be swung into place when the doors are raised and closed. These seats fit nicely between the tracks. Bolts 15 21, 21 can be employed to fasten the doors. In this manner side aisles 22, 22 are formed at the sides of the compartment, and for convenience doors 23, 23 are formed at the front of the vehicle for entrance to this compartment.

In very stormy weather it is sometimes desirable to convert the car into a chapel car, so that the services ordinarily performed at the grave can be said in the car with much 25 greater convenience. To permit of this being done the partition between the compartments is provided with a door 24 and windows 25 which may be opened, or if desired the entire partition may be made removable.

Having described the invention what we claim as new and desire to secure by Letters Patent is:—

1. In a body for an auto-funeral car, in combination, a passenger compartment, provided with transverse stationary and movable seats and transverse and side aisles, a casket compartment, a partition between the compartments, side entrances to the passenger compartment and front entrances to the casket compartment, dropping side walls for the casket compartment, said side walls being adapted to form platforms for the introduction of the casket to said casket compartment.

2. In a funeral car, in combination a rear passenger compartment provided with side entrances, a front compartment adapted to contain a casket, a wheeled support for said casket, hinged sides for said compartment, tracks, portions of which are upon said hinged sides and portions upon the floor of said compartment and upon which said wheeled support is designed to travel, and removable seats in said front compartment.

3. In a funeral car, the combination with

a rear passenger division, of a front casket division, a chauffeur's division, removable seats in the casket division, stationary seats in the rear passenger division, a door between said casket and passenger divisions, and means for supporting a casket in and removing it from the casket division.

4. In a body for an auto-funeral car, the combination of, a rear passenger compartment having side entrances, a front casket compartment having front entrances, hinged doors hinged seats upon said doors, and track portions transversely laid in said casket compartment and transversely crossing said doors, said track portions pivoted together to form hinges and hinge straps for said doors.

5. In a body for an auto-funeral car, in combination, a passenger compartment, a casket compartment and a chauffeur's compartment, a partition between the casket compartment and the passenger compartment, a door and windows in said partition, whereby means of communication between the casket and passenger compartments is afforded and sounds produced in one compartment are audible in the other, tracks transversely laid on the floor of the casket compartment, drop doors in the walls of the casket compartment, tracks laid upon said drop doors and adapted to form continuations of the tracks on said compartment floor at the adjacent ends of the tracks on said floor and doors being pivoted together to form hinges for said doors.

6. In a body for an auto funeral car, in combination, a passenger compartment, fixed and movable seats therein, arranged to provide longitudinal and transverse aisles, a casket division, drop doors for said casket division, a support for said casket, in said casket division, movable seats in said division about said casket, a partition between said passenger compartment and said casket division, windows in the upper portion thereof, a door in said partition and doors in the exterior walls of said compartments for ingress and egress.

In testimony whereof, we hereunto set our hands this 3d day of September 1908.

JAMES W. BUTLER.

FRED R. BRIGGS.

EDWIN H. CLARK.
